(57) **CLAIM**

The ornamental design for a rear end portion of a motor vehicle and/or toy replica thereof, as shown and described.

DESCRIPTION

FIG. 1 is a left, front perspective view of a rear end portion of a motor vehicle and/or toy replica thereof showing our new design;

FIG. 2 is a right, front perspective view thereof;

FIG. 3 is a left, rear perspective view thereof;

FIG. 4 is a right, rear perspective view thereof;

FIG. 5 is a front view thereof;

FIG. 6 is a rear view thereof;

FIG. 7 is a left side view thereof;

FIG. 8 is a right side view thereof; and,

FIG. 9 is a top view thereof.

The claimed design is indicated by the relatively dark portions in the figures. The relatively light portions form no part of the claimed design.
